PUZZLE

Henry M. Slocum, New York, N. Y.

Application June 30, 1943, Serial No. 492,912

4 Claims. (Cl. 273—157)

1

This invention relates to a new and improved amusement device or puzzle, similar in some respects to jig-saw puzzles, but having additional features cooperating therewith to provide a new and fascinating puzzle combination which may be solved only in accordance with a new and different technique or mode of operation.

It is an object of the invention to provide a simple, inexpensive amusement device or puzzle which has all of the advantageous features of conventional jigsaw puzzles, yet which is more interesting and absorbing, since it requires not only keen perception and imagination to determine whether the respective puzzle pieces should be placed in relation to others, but, in addition, requires a high degree of manual dexterity, skill and delicacy of touch, in order to so manipulate the device as to position the pieces in their proper relation.

Jigsaw puzzles of the prior art comprise a plurality of irregularly and arbitrarily shaped pieces cut from a picture mounted upon a thin backing slab of wood, cardboard or the like. In solving such puzzles, the person attempts to fit together the pieces in their original relation, using the hands to match the various pieces and to try to fit different pieces in the different localities, until the correct solution has been reached, whereupon the original picture may be examined and enjoyed with a feeling of satisfaction and accomplishment.

The jigsaw puzzle of the present invention eliminates the manual handling of the individual pieces, yet requires that the pieces be assembled in the original relation, as cut by the jigsaw from the original picture. Thus, the puzzle of the present invention has all of the features of conventional jigsaw puzzles and the interest, fascination and satisfaction of accomplishment, which results from fitting the pieces into their proper places. However, the process of solving the puzzle is rendered more difficult and interesting, for the reason that the individual pieces cannot be handled as units and readily placed in proper position. On the contrary, the puzzle must be solved by shaking, tapping and otherwise carefully manipulating a case in which the pieces are contained and through which they are visible. Thus, the puzzle has many of the characteristics of puzzles of the "pigs-in-clover" type, wherein a plurality of balls or other objects must each be moved from one position to another by tipping, shaking or tapping a container.

From the foregoing, it will be seen that it is an object of the present invention to combine

2

in a single puzzle device, the desirable features of puzzles of the jigsaw type and puzzles of the manipulative, shaking or tapping type.

In accordance with the present invention, a jigsaw puzzle is cut from an appropriately mounted picture of predetermined overall size and shape. A casing is provided, having a base of substantially the size and shape of the original picture, though preferably slightly larger, and also having a cover spaced from the base a suitable distance and through which the pieces of the puzzle, contained within the casing, may be viewed. Preferably, the cover is of transparent material, such as Celluloid, Cellophane, glass or the like, although any material which prevents access to the puzzle pieces, yet permits them to be seen, may be employed.

Preferably, certain of the pieces of the puzzle are substantially permanently secured to the base in their proper relation to each other and to the margins of the base, so that the puzzle is always at least partially solved and a hint or indication is given to the user as to the manner in which the remaining pieces should be assembled. If it is desired to make the puzzle more difficult, a fewer number of pieces may be secured to the base, or all of the pieces may be loosely positioned within the casing.

It is important that the vertical dimension between the base and the transparent cover be no greater than the size of the puzzle pieces contained therein, so that the pieces cannot be overturned and their upper faces hidden from view, when the case is being manipulated.

In the accompanying drawing an illustrative embodiment of the invention is shown, in which:

Figure 1 is a perspective view of the device with the puzzle solved and the pieces in their properly assembled relation.

Figure 2 is a horizontal sectional view with the loose pieces removed.

Figure 3 is a plan view with the loose pieces in scattered relation, and

Figure 4 is a transverse section on line 4—4 of Figure 1.

As shown in the accompanying drawing, the case for the puzzle comprises a base 10 mounted within a cardboard box-like inner case comprising a bottom 11 and turn-up wings integral therewith and constituting side and end members 12 and 13, respectively. Upon the upper edges of the side and end members, there is a transparent cover 14, having down-turned marginal flanges 15 embracing the side and end members and held in place by metallic angle strips 16, 17, joined

together at opposite corners in any suitable manner, and having inwardly turned upper and lower flanges 18, 19 holding the parts in assembled relation. If desired, a second, reinforcing bottom member 20 may be positioned below the bottom 11 and above the lower flanges 19.

The base and bottom members and the side walls may be made of cardboard or the like, while the cover 14 is preferably of Celluloid, cellulose acetate sheet material, or any transparent synthetic resin, or even glass. The outer side walls 16, 17 of the case may conveniently be formed from aluminum stampings.

The puzzle within the case is formed by cutting, stamping or jigsawing irregularly shaped pieces from a mounted picture of predetermined overall size and shape, corresponding substantially to the size and shape of the base 10. The lines upon which the mounted picture is cut are indicated in Figure 1, thereby providing individual pieces 21-33, both inclusive.

As indicated in Figure 2, the pieces 21-26 are secured to the base, as by adhesive, in substantially their original relation, except that slight spaces 35 are left between the pieces to compensate for the saw cut and to leave the remaining, unfilled spaces between the fixed pieces slightly larger than the loose pieces, thereby facilitating the reception of the loose pieces therein. The loose pieces 27-33 are shown in Figures 3 and 4 as being indiscriminately positioned relative to each other and to the fixed pieces. It should be noted that the vertical dimension between the base 10 and the cover 14 bears such a relation to the longitudinal and transverse dimensions of the loose pieces that the latter cannot be overturned, with their upper surfaces facing downwardly and their bottoms exposed to view.

It should be understood that the pieces secured to the base may be arbitrarily selected when the puzzle is manufactured, and that differently positioned pieces in similar puzzles may constitute the fixed pieces. Moreover, a greater or lesser number of pieces may be fixed to the base, depending upon the ease or difficulty of solution desired.

In solving the puzzle, the case is manipulated by shaking, tapping and otherwise handling it, until one after another of the loose pieces 27-33 drop down into their appointed spaces, adjacent the fixed pieces and the side walls of the case. Preferably, the base of the case is made slightly larger than the puzzle, so that the pieces may be received in proper position with a relatively loose fit.

When the loose pieces have been assembled, as indicated in Figure 1, the picture is clearly visible and the person solving the puzzle has the same satisfaction usually enjoyed by persons putting together standard jigsaw puzzles, with the added satisfaction of accomplishing the task entirely by manipulating the casing in which the pieces are contained.

It must be understood that the invention is

not limited to the details of construction shown in the accompanying drawing and described above, but covers all modifications coming within the scope of the appended claims and their equivalents.

I claim:

1. A puzzle comprising, in combination, a case having a base and a transparent cover, and a plurality of arbitrarily shaped puzzle pieces of jigsaw type in said casing with their upper faces visible through said cover and being of a size, when assembled, substantially coextensive in area with said base, certain of said pieces being loosely contained in said case and others being permanently secured to said base in proper relation thereto and to each other, whereby the loose pieces may be assembled, by shaking or otherwise manipulating the casing.

2. A jigsaw type puzzle comprising a plurality of irregularly and arbitrarily shaped pieces adapted to be assembled in only one proper relation in which the assembly has a margin of predetermined size and shape, and a casing enclosing the puzzle having a base of substantially the size and shape of the puzzle when assembled and a cover above the base through which the puzzle may be viewed, whereby the puzzle may be assembled upon the base by shaking and otherwise manipulating the casing, a plurality of said puzzle pieces being permanently secured to the base in proper, assembled relation to each other and to the base, whereby assembly of the loose pieces is facilitated.

3. A jigsaw type puzzle comprising a plurality of irregularly and arbitrarily shaped pieces cut from a mounted picture of predetermined overall size and shape and adapted to be re-assembled in substantially their original relation, and a case enclosing said pieces having a base of substantially the same shape and size as the original picture and a transparent cover preventing access to the pieces but permitting visual observation thereof as the case is manipulated in an attempt to fit the pieces together.

4. A jigsaw type puzzle comprising a plurality of irregularly and arbitrarily shaped pieces cut from a mounted picture of predetermined overall size and shape and adapted to be re-assembled in substantially their original relation, and a case enclosing said pieces having a base of substantially the same shape and size as the original picture and a transparent cover preventing access to the pieces but permitting visual observation thereof as the case is manipulated in an attempt to fit the pieces together, certain of said pieces being permanently secured to the base in proper assembled relation to each other and to the base, said cover being spaced from the base a greater distance than the thickness of two of said pieces, whereby the loose pieces may slide over each other and over the secured pieces during manipulation of the puzzle, to move the loose pieces into proper relation to each other and to the secured pieces.

HENRY M. SLOCUM.
